United States Patent Office

Des. 187,723
Patented Apr. 19, 1960

187,723

ELECTRICAL FACIAL VIBRATOR OR SIMILAR ARTICLE

Samuel L. McNair, Whitman, Mass., and
Lawrence E. Fenn, Bridgeport, Conn.

Application March 13, 1959, Serial No. 54,972

Term of patent 14 years

(Cl. D83—1)

Fig. 1.

Fig. 2.

Fig. 3.

Fig. 4.

Fig. 5

Fig. 1 is a front elevational view of an electrical facial vibrator or similar article embodying our new design, the rear not shown being substantially like the front shown;

Fig. 2 is a side elevational view thereof;

Fig. 3 is a top plan view thereof;

Fig. 4 is a bottom plan view thereof; and

Fig. 5 is a fragmentary vertical cross-sectional view thereof taken on the line 5—5 of Fig. 1.

We claim:

The ornamental design for an electrical facial vibrator or similar article, substantially as shown and described,
